UNITED STATES PATENT OFFICE.

LOUIS MAXWELL POTTS, OF BALTIMORE, MARYLAND, ASSIGNOR TO AUSTIN McLANAHAN, OF BALTIMORE, MARYLAND.

SELECTIVE SIGNALING APPARATUS.

1,299,608.

Specification of Letters Patent.

Patented Apr. 8, 1919.

Original application filed October 11, 1913, Serial No. 794,633. Divided and this application filed May 9, 1916. Serial No. 96,323.

To all whom it may concern:

Be it known that I, LOUIS MAXWELL POTTS, a citizen of the United States, residing at Baltimore city, State of Maryland, have invented certain new and useful Improvements in Selective Signaling Apparatus, of which the following is a specification.

The present application constitutes a division of my application for Letters Patent of the United States, for improvements in selective signaling apparatus, filed October 11, 1913, Serial No. 794,633, and relates particularly to the transmitting apparatus disclosed in said application.

15 The primary object of this invention is the production of transmitting apparatus for use in printing telegraph systems, which shall be capable of substitution for the usual Morse key or Wheatstone automatic transmitter on 20 Morse circuits, without otherwise changing the line equipment, and by apparatus which shall require a minimum of adjustment for accurate operation when once set up.

These objects are attained largely by reducing electrical parts of the apparatus to a minimum; by employing a single transmitting contact; an extremely accurate and constant mechanical timing means, and by making the operation of the apparatus dependent on the condition of the line over which it operates, so that when connected in a Morse closed circuit, for example, one operator's transmitting apparatus may be stopped by opening the circuit at another station, the 35 equivalent of the so-called Morse "break."

My invention will be better understood by reference to the accompanying drawings, in which:

Figure 1, is a front elevation of one form 40 of machine embodying my invention;

Fig. 2, a side elevation thereof, partly in section;

Fig. 3, a semi-diagrammatic front elevation of the train of driving gears, as viewed 45 from the rear of the machine;

Fig. 4, a semi-diagrammatic view showing the arrangement of cams on the starting and combination bars, and their relation to the key levers;

50 Fig. 5, a fragmentary sectional elevation

showing the manner of supporting the starting and combination bars;

Fig. 6, a fragmentary vertical sectional elevation showing the timing balance and its starting and stopping mechanism;

Fig. 7, a fragmentary vertical sectional elevation showing the mechanism for transmitting the starting impulse, and for creating a lag between signals as hereinafter described;

Fig. 8, a detail perspective view of the movable transmitting contact;

Fig. 9, a fragmentary sectional elevation showing the mechanism for locking the keyboard;

Fig. 10, a detail view in side elevation of the selector mechanism as viewed from the opposite side from Fig. 2;

Fig. 11, a fragmentary sectional side elevation showing the transmitting switch and 70 a part of the mechanism for operating the same;

Fig. 12, a detail side elevation of the balance and escapement mechanism, showing the balance in the act of oscillating in a 75 counter-clockwise direction;

Fig. 13, a fragmentary detail side elevation to show more clearly the operative relation between the safety-pin and passing hollow of the safety-roller of the escapement 80 mechanism;

Fig. 14, a fragmentary top plan view, partly in section, showing the relation of the controlling magnet armature to the parts which it actuates and controls;

Fig. 15, a developed view to show the relative angular positions in which the various cams are mounted on the timing shaft;

Fig. 16, a fragmentary top plan view showing the lateral spacing or positions of 90 said cams on the timing shaft, and also showing the friction clutch for operating this shaft;

Fig. 17, a similar view of the friction clutch of the type-wheel shaft and the timing shaft;

Fig. 18, a diagram illustrating the current as transmitted for two signals, and

Figs. 19 to 22, inclusive, diagrams showing various types of Morse circuits equipped 100

with the transmitting apparatus embodying my present invention.

The machine herein shown comprises, among other parts, a main frame which includes a base 1 on which is supported a keyboard and other parts of the machine hereinafter described.

The keyboard comprises a series of keys 2 and a space bar 3, mounted upon the ends 10 of a series of key levers 4 pivotally supported in the machine frame. These levers are held in alinement by two vertically slotted guide combs 5 and 6, and operate against the tension of springs 7 which return them to their normal positions. The arrangement of the keys is preferably that of a standard typewriter.

The function of these key levers is to operate a starting bar 8 and a series of combination bars 9^a, 9^b, 9^c, 9^d and 9^e, which extend transversely across and above the upper edges of said levers adjacent to their rear ends.

These bars 8 and 9^a—9^e are mounted for 25 longitudinal movement in individual vertical slots 10 in two uprights 11 and 12 on the machine base, and are confined within said slots by horizontal pins 13, 14, and 15, 16 (see Fig. 5).

30 The operation of the bars 8 and 9^a—9^e by the key levers is effected by the engagement of beveled edges 17 of these levers with a series of cams 18 on the starting bar, and a series of cams 19 on each combination bar, the said bars being returned to their normal positions by individual springs 20.

The starting bar 8 is shifted on the operation of any of the key levers, and for this reason it is provided with a similar cam 40 18 for each key lever, each such cam having a face slanting in such direction as to shift this to the right when engaged by the beveled edge 17 of any key lever. (See Figs. 4 and 5).

45 The arrangement of cams 19—19, on the combination bars, however, is different on each such bar as only a certain one or combination of these bars is operated by each key lever.

50 The arrangement of these cams on the combination bars will vary according to the system of combinations employed. The arrangement of the cams on all of said bars of this particular machine may be had from 55 Fig. 4. Assuming the vertical dotted lines to represent the positions of the key levers, as viewed from above, the relative positions of the various cams with respect to these levers may be readily obtained. In the particular machine herein shown, the five unit system of combinations is employed, and for this reason there are five combination bars.

Only those cam faces which slant upward from right to left on the lower edges 60 of the combination bars 9^a—9^e act in con-

junction with the key levers to shift said bars in the required combinations. The cam faces which slant in the other direction (upward from left to right Fig. 4) are merely for the purpose of preventing the depression, during the transmission of a signal, of some other key than the one operated to send that signal, as hereinafter more particularly described.

The shifting of bars in various combinations by the action of the key levers on cams on said bars is old and well known in the art.

The starting bar 8 is provided on its upper edge with a notch 21 and cam 22. Within 80 this notch normally rests the lower end of a vertically movable slide 23, having a beveled edge 24 which rests, under the tension of a spring 25, against the cam 22 (see Fig. 7). The starting bar is also recessed as at 26 for 85 a purpose which will be stated later.

Each combination bar 9^a—9^e is provided with a notch 27 and cam 28 similar to those of the starting bar, and these cams 28 are in 90 similar coöperative relation respectively with the lower beveled ends of a series of vertical slides 29^a, 29^b, 29^c, 29^d, and 29^e, each of which is held against a cam 28 under the tension of an individual coil spring 30. (See Figs. 2 and 10.)

95 Slides 23 and 29^a—29^e are mounted for movement in a vertical plane in individual slots 31 and 32 in guides 33 and 34 respectively, secured rigidly between two upright plates 35 and 36 made fast to the frame of 100 the machine as shown most clearly in Fig. 2. These slides must travel vertically without any angular displacement and for this reason are held against such displacement in the slots 31 by plates 37 and 38 and in slots 105 32 by plate 38'.

110 Mounted in the same vertical plane with starting slide 23 and extending above it (see Fig. 7) is a starting lever 39 having a beveled lower end 40 extending into the same slot in guide 33 as the slide 23. This lever has near its lower end a shoulder 41 which rests upon the upper edge of guide 33, while the upper portion of said lever rests in an open end slot 42 in a guide 43. 115 On one of its edges between guides 33 and 43, lever 39 is provided with a cam 44, the function of which is to coöperate, as hereinafter described, with a rotatable cam 45 fast on a square shaft 46, journaled for rotation in plates 35 and 36. A spring 47 bears against lever 39 at a point above the axis of cam 45 and on the opposite side of said lever from said cam so as at all times to exert a pressure on said lever from right to left, 120 Fig. 7. In Fig. 7 the parts are shown in their normal positions, that is, the positions they occupy when no signals are being transmitted. At such a time, cam 45 will engage cam 44 on the starting lever in the central 125 130

position, as shown, when the lever 39 will occupy a tilting position with its foot kicked outward to the right.

When the starting bar 8 is shifted to the right, (Fig. 7) as it will be when any key is operated, this will cause slide 23 to rise to such an extent that a beveled corner on the upper end thereof engages the beveled portion 40 of lever 39 and forces the lower end 10 of said lever to the left, thus causing the said lever to turn in a vertical plane on cam 45 as a fulcrum, sending its portion above said fulcrum to the right. On the opposite edge of this lever from cam 44 and above it, 15 is an extension 48 which at all times engages a universal bar 49 carried by and insulated from a depending arm 50 of a bell crank lever 51 fulcrumed between two pivot screws 52 and 53 mounted in arms 54 and 55 20 secured to an insulating block 56 held between plates 35 and 36. The horizontal arm of this bell crank lever extends through an opening 57 in block 56, and carries on its outer end an electrical contact 58 which is 25 adapted to travel between and alternately engage adjustable stationary contacts 59 and 60, contact 58 being normally held in engagement with contact 60 by spring 61 which also acts to hold universal bar 49 30 against cam extension 48.

Contact 58 is carried on a hinged extension on lever 51, the said extension comprising a bent metal plate 62 fitting over the end of said lever and pivotally secured thereby 35 by pin 63. Spring 61 is attached at one end to extension 62 at a point in the rear of its pivot, and at the other end to a milled thumb screw 64 by which the tension of the spring may be adjusted. Through the action of 40 hinged extension 62, contact 58 is caused to wipe contact 59 on each engagement thereof, and thereby make more certain electrical connection. Wiping contacts, however, are old and well known in the art and nothing 45 new is here claimed for this detail which may or may not be employed, as desired.

Engagement of contact 59 by contact 58 results in the completion of a circuit through the coils of an electro-magnet 65.

As we are not at this time particularly concerned with any electrical connections, these need not at present be traced. It will be assumed that magnet 65 is in series with contacts 58 and 59. The electric circuits will 55 be taken up later on in this description.

Magnet 65 is mounted for vertical adjustment upon a screw 66 carried in a bracket 67 made fast to an insulating block 68 held between plates 35 and 36. This magnet is provided 60 with an armature 69 pivotally supported between two brackets 70 and 71 secured to block 68. This armature is normally held down against an adjustable stop 72 by a spring 73, the tension of which may be adjusted by thumb screw 74. The up-

ward movement of armature 69 is limited by an adjustable stop 75.

Extending over the forward edge of this armature is an arm 76 on a vertically movable slide 77 (see Fig. 6) mounted on slots 70 in two horizontal guide bars 78 and 79 held rigidly between plates 35 and 36, and retained in said slots by plates 80 and 81.

Slide 77 controls the starting and stopping of the timing mechanism, which will now be 75 described.

When magnet 65 receives the starting impulse, as described, it draws armature 69 upward, and this raises slide 77 against the pull of a spring 82. The lower end of this 80 slide when in the down or normal position, acts as a stop for an arm 83 fast upon the periphery of a balance 84. This balance is fast upon a shaft 85 journaled for rotation in plates 35 and 36. When the slide 77 is 85 thus sent upward, the balance becomes released and starts oscillating.

This balance oscillates under the control of a helical spring 86 having one end rigidly fastened to the balance at 87, and the 90 other end similarly fastened as at 88 to plate 35, (see Figs. 6 and 10) so that the number of turns in the spring is a whole number, lacking approximately 90° according to the well known practice in chronometer construction. The size of the wire of the spring 86 and the weight of the balance are so chosen that one-half of a complete (forward and back) oscillation of the balance occupies the time necessary for one unit impulse of 100 the signal. This period of oscillation is chosen as being the most convenient, but is not necessarily essential. A unit impulse could correspond to a quarter period of the oscillation of the balance. It is, however, 10 important that the unit impulse correspond to some multiple of the period of the balance.

This balance has on its circumference two mean time screws 89 which are used to bring 110 the balance to the desired standard. This is done by choosing screws of the proper weight. If the balance is too fast, a larger screw is inserted. Two rating screws 90 are inserted in the rim of the balance at about 115 90° from the screws 89. Screws 90 are used for the purpose of changing the rate of the machine in words per minute to adapt it to different lengths of line and different operating conditions. The balance is so constructed that it has a rate equal to the maximum rate desired, and this rate is brought down to that required in any particular case by different size screws 90.

The power which actually oscillates the 120 balance 84 is transmitted to it through an escapement mechanism comprising an escape wheel 91 fast on timing shaft 46; an anchor 92 fast on rock shaft 93; safety roller 94 fast on shaft 85; an impulse pin 95 fast on

said roller, and adapted to engage a notch 96 in the lower end of the anchor, and a safety pin 97 adapted to engage "passing hollow" 98 in the safety roller 94. This escapement mechanism is substantially the same as that commonly known as the "lever escapement," used in the clock and watch making art, so need not here be more fully described.

10 Escape wheel 91 has six teeth, so that three complete oscillations of the balance will allow the timing shaft 46 to rotate one-half a revolution, which is the length of time required for the transmission of one complete signal. At the end of this half revolution, the rotation of shaft 46 is stopped by the engagement of stop arm 83 on the balance with slide 77 which drops into the path of arm 83 on the balance, caused by the dropping of the nose of an arm 99 on said slide (see Fig. 6) into either one of two diametrically opposite notches 100 in the periphery of a cam 101 fast on timing shaft 46. Balance 84 is, therefore, started and stopped at identically the same point each time. Directly after shaft 46 starts to rotate, the nose of arm 99 rides up on the elevated portion of the cam, where it remains until said cam has rotated about one-half a revolution, thereby positively holding said stop slide out of the path of balance arm 83 for the proper length of time.

The timing shaft 46 is power driven through a train of gearing (see Figs. 2 and 3) comprising a gear 102 mounted on said shaft and adapted to making driving connection therewith through a friction clutch hereinafter described; a pinion 103 meshing with said gear and fast to a gear 104; an idler 105 meshing with gear 104; a pinion 106 meshing with idler 105 and fast to a gear 107, and a pinion 108 meshing with gear 107 and fast on the armature shaft 109 of an electric motor 110.

45 Any suitable source of power, however, may be substituted for this motor. It is not necessary that the speed of the driving mechanism be constant, but only that it is run sufficiently fast. For a rate of forty words 50 per minute, for example, shaft 46 should rotate about one hundred and seventy-five revolutions per minute.

55 Gear 102, as above pointed out, is not connected directly to timing shaft 46, but drives it through a friction clutch shown in detail in Fig. 17. Gear 102 itself, forms one of the friction members of this clutch, and for this purpose is preferably made of fiber. This gear is mounted to rotate on a metal sleeve 111 fast on a cylindrical extension of shaft 46, and this sleeve is provided with a friction disk 112 which lies flat against one face of gear 102. Against the other face of this gear is another friction disk 113. Friction is created between gear 102 and disks

112 and 113 by a spring 114 held under compression by a recessed nut 115 upon the end of the shaft 46. A pin 116 passes diametrically through shaft 46, through the sleeve 111, and into radial slots 116' in the hub of disk 113, thus holding disk 112 fast to shaft 46 both against rotation relative thereto and against sliding laterally thereof, and holding disk 113 against rotation relative to shaft 46, but permitting said disk to move laterally of said shaft. Therefore, as long as the stop 77 is against balance arm 83, shaft 46 will be held against rotation, but as soon as this stop is removed, said shaft is set free and will be driven by the friction between plates 112 and 113 and gear 102. When shaft 46 is held against rotation, gear 102 nevertheless continues to rotate.

Immediately after the timing shaft 46 starts to rotate, cam 45 passes from engagement with slide cam 44. (See Fig. 7.) This slide will then be pushed to the left under the action of spring 47 and universal bar 49, whereupon contact 58 breaks connection with contact 59, unless the combination bar 9^a has been operated, thus terminating the starting impulse. If the signal being sent involves the operation of combination bar 9^a, contact 58 will not break connection with contact 59 at the time above stated, but will remain in contact therewith for a time depending upon which other of the combination bars has been operated for that particular signal. This, however, will be more readily understood after the operation 100 of the transmission of the actual signal impulses has been described.

Passing now more particularly to the mechanism which co-operates with the combination bars and vertical slides 29^a—29^e 105 to transmit the impulses which form the actual signals as contra-distinguished from the starting impulse, this comprises, among other parts, five cams 117^a, 117^b, 117^c, 117^d and 117^e fast upon the timing shaft 46, 110 which co-operate respectively with five transmitting levers 118^a, 118^b, 118^c, 118^d and 118^e to operate through the universal bar 49 the movable contact 58.

Cams 117^a—117^e are all of the same 115 shape as cam 45 and are so arranged on the shaft 46 that succeeding ones of said cams (117^a—117^e) are angularly displaced 30° behind the preceding one about the axis of said shaft (see Fig. 15) and are held against 120 lateral movement on said shaft by spacing collars 46'.

The transmitting levers 118^a—118^e are mounted in the same vertical planes respectively with cams 117^a—117^e and to one side 125 thereof as shown most clearly in Figs. 2 and 10. The upper ends of these levers rest in individual open end slots in guide bar 43, while their lower ends extend into the same slots in guide 33 as receive the upper ends 130

of the slides 29^a—29^e, said levers being supported upon the upper edge of guide 33, each by a lug 119, and their upward movement limited by lug 120 engaging the lower side of the guide 43. (See Fig. 11.) Each of these levers is normally held in the position shown in Fig. 11 under the tension of an individual spring 121, bearing upon the backs of said levers at a point higher than the axis of shaft 46. The levers 118^a—118^e each have a cam 122 adapted to be engaged each by a different one of cams 117^a—117^e, and each lever is also provided with an extension 123 adapted to engage universal bar 49 of the transmitting contact lever. The operation of these levers 118^a—118^e by the slides 29^a—29^e is substantially the same as that described with relation to the starting lever 39. According to which of the slides 29^a—29^e is or are raised by the operation of any particular key, the lower ends of corresponding levers 118^a—118^e will be held by said slides against movement to the right. Then, as shaft 46 continues its rotation, cams 25 117^a—117^e will successively engage cams 122 on levers 118^a—118^e. Clearly then, those levers 118^a—118^e, the lower ends of which are restrained from movement to the right by the operated slides 29^a—29^e will move to the right at their upper ends, and in so doing will act through the universal bar 49 and lever 50 to send the contact 58 into engagement with contact 59 once for each lever 118^a—118^e so operated. Levers 118^a—118^e 35 are returned to normal by springs 121 and universal bar 49, the latter action under the tension of spring 61.

As to those levers 118^a—118^e whose slides 29^a—29^e have not been operated, the case is 40 different. These levers being less restrained at their lower ends, than at their upper ends, due to the pressure of springs 121 and 61, above the axis of cams 46, will kick out at their bottoms to the right. Therefore, the 45 extensions 123 of these levers have no operative effect on the bar 49, and hence will not operate contact 58. Each of the levers 118^a—118^e is capable of two degrees of motion, but restrained from movement by unit 50 equal pressure in two degrees, the cams 117^a—117^e tending to operate said levers in succession, and the slides 29^a—29^e selectively acting to positively lock said levers from motion in the way of least restraint and to 55 compel their motion in a direction of greatest restraint. Therefore, for each slide 29^a—29^e raised by the combination bars, contact 58 will be sent into and remain in engagement with contact 59 for a definite interval, 60 the time of which corresponds to a unit impulse, and one or more of these impulses go to make up each signal according to the combination.

It will be seen from the foregoing description that whenever a key is operated, a start

impulse is transmitted to magnet 65 which immediately releases the balance and therefore starts it into motion in phase with this start impulse, and the subsequent beats or oscillations of the balance so time the opening and closing of the transmitting contact that the impulses of the signal corresponding to the said start impulse will necessarily be in phase with the balance. In other words, the oscillations of the balance and 75 the unit impulse periods of a signal bear a definite phase relation.

Each signal period may be regarded as divided into six equal time intervals represented diagrammatically in Fig. 18 by the 80 spaces indicated S, A, B, C, D and E between the vertical dotted lines. Each of these intervals represents the time that the contact 58 remains against the contact 59 to transmit a unit impulse. The space S indicates the interval of the starting impulses, and the spaces A to E the intervals of the five unit signal impulses which are employed in various combinations to form the signals proper.

In Fig. 18 the solid lines above the line O—O of zero current represent the current on the line when two signals are transmitted, one calling for the B. C. combination, and the other for the A B C D E combination.

In the case of the signal calling for the A B C D E combination, the current is continuously on the line from the commencement to the end of the signal period, as indicated, embracing all the spaces S to E.

Combinations of impulses may therefore be formed ranging from the employment of one impulse for each of the spaces A to E, to the employment of one impulse of a duration equal to all such intervals combined. 105 With the five unit system here employed, thirty-two such combinations may be had.

It will be seen that whenever a combination is transmitted which involves the A impulse position, the starting impulse does 110 not fall to zero, but merges into the A impulse. This is due to the fact that the operation of the combination bar 9^a, which sends the A impulse, operates through slide 29^a, lever 118^a which holds the universal bar 49 out and the contacts 58 and 59 closed notwithstanding cam 45 has passed from the starting lever 39. (See Fig. 11).

The exception mentioned in a foregoing portion of this description, to the fact that 120 on the passage of cam 45 from cam 44 the contacts 58 and 59 separate, will now be more fully understood.

The spaces indicated L represent the lag which is automatically produced between 125 successive signals, when the machine is operated at maximum speed, as hereinafter more particularly described.

The combination for each signal may be had from Fig. 4 by noting the relation be-

tween the dotted lines indicating the key levers, and the cam lugs on the different combination bars 9^a—9^b. These combination bars correspond to the five impulse periods 5 A to E Fig. 18, the impulses being transmitted in combinations depending upon which of said bars are operated. For example, the operation of the 9^a and 9^b bars will send the A B impulse combination, the operation of the 9^c bar the C impulse, etc.

There should always be between successive signals a lag great enough to prevent any signal from blending with the starting impulse of a succeeding signal, and this lag 10 should preferably be equal to the time of a unit impulse in order that at any given speed of transmission the length of the line operable may be a maximum. When the machine is not operated at its maximum speed, 15 a natural lag will be produced between successive signals due to the pauses of the operator. When, however, there are no such pauses by the operator, some means should be provided for automatically producing 20 this lag. This is effected in the present machine by providing means which will automatically retard the action of the contacts 25 58 and 59 in closing to send the starting impulse of a signal, under the conditions 30 above stated. For this purpose, starting lever 39 (see Fig. 7) is provided at its upper end with an offset or hooked extension 124, and adapted to coöperate, as hereinafter described, with this extension is a pin 125 carried by a slide 126 mounted for vertical 35 movement in fixed guides 127 and 128, said slide being normally pulled down under tension of a spring 129. This slide is provided with a downwardly extending arm 130 having 40 a beveled end adapted to rest upon the periphery of a cam 131 fast on the timing shaft 46. Now, as cam 131 rotates, it raises slide 126, and as this slide nears the extreme 45 end of its upward motion, pin 125 engages the hooked extension 124 of lever 39 and raises this lever so that its lower extremity cannot engage the upper end of slide 23 even when a key is depressed, so that contacts 58 and 60 will remain closed until slide 50 39 is pushed downward by pin 125. When cam 131 has made a half revolution, which is the end of a signal period, arm 130 will drop from the elevated portion of this cam to the position shown in Fig. 7, thus causing 55 pin 125 to move lever 39 downwardly, and in doing so this lever is rocked about cam 45 as a pivot by the engagement of the lower tip of said lever with the upper tip of slide 23, and this rocking motion of lever 39 causes the engagement of contacts 58 and 60 60 and the transmission of the starting impulse. Therefore, when the machine is operating at maximum speed, with no pauses by the operator between successive signals,

the starting impulse is always sent by the 65 downward movement of slide 126 rather than by the upward motion of slide 23, thereby causing a delayed closing of the contacts 58 and 59 for the starting impulse. The weight of slide 126, the strength of spring 70 129, and the drop of slide 126 are so chosen that the desired lag is obtained.

Normally all of the keys of the keyboard are unlocked. The operation of any key, however, not only locks that key and its 75 combination bar or bars, but locks all the other keys and their combination bars as well, against further operation until the completion of the signal. This is effected by the following mechanism. (See Fig. 9.)

Each combination bar 9^a—9^e is provided on its upper edge with two notches 132 and 133. Extending transversely across all of these combination bars and, in the normal or unoperated position of said bars, lying directly above notches 133, is a locking bar 134 having a knife edge adapted to engage with said notches. This locking bar is carried on the lower end of a slide 135 adapted to move vertically in guides 43, 33 and 34. 85 This slide is provided with an offset extension or arm 136 having a cam portion 137 adapted to lie in the path of a rotatable cam 138 made fast on timing shaft 46. Normally this cam occupies the position shown in Fig. 9, at which time it holds slide 135 in the elevated position shown, under the tension of a downwardly pulling spring 139. Immediately after the timing shaft 46 is started 90 into rotation, as described, cam 138 passes from cam 137, thereby allowing slide 135 to be pulled downward. When this happens, the knife edge of bar 134 will be sent into notches 132 of the operated combination bars and into notches 133 of the unoperated combination bars, thus locking both sets of bars against further operation until the signal has been transmitted. When it is attempted 95 to depress any of the keys during the transmission, they will be held from operation by the cams on the combination bars. At the end of a signal period, or when the timing shaft 46 has made a half revolution, cam 138 will again raise slide 135 and unlock the 100 keyboard.

The notch 26 on the starting bar is merely to allow locking bar 134 to descend.

In Fig. 19 is shown connections for a method of operation particularly adapted for short distances. In this case contacts 58 and 60 of each machine are normally closed, and these contacts as well as magnets 65 are in series with a single source of current 140 at one end of the line. The diagram shows two of my machines on a line. In this case 120 any machine is ready to transmit at any time, and if magnets 65 are employed to receive also, as described in my aforesaid 125

co-pending application, it is not necessary to operate a switch to change from sending to receiving.

In Fig. 20 is shown the connections for 5 three stations on a way-wire according to the well known American Morse closed circuit method. In this case, a line battery 142 is required at one station only, and contacts 58 and 60 are connected directly in 10 the main line in series. At each station a main line relay 143 is connected in series with contact 60. Magnet 65 on my machine, at each station, is connected in series with a contact of the main line relay, just 15 as is connected the sounder in the ordinary Morse circuit, except that in the present case the magnet 65 is connected in series with the back contact 144 of the main line relay instead of the front contact thereof. 20 The magnet 65 of each machine is in series in its local relay circuit with a battery 145 and suitable resistance 146.

Fig. 21 shows the connections for three stations on a way-wire operated according 25 to the British open circuit method. In this case the line is normally closed, but at this time there is no battery on the line. This method requires a battery 147 at each station, which is thrown onto line in series 30 with magnet 65 and contact 58, each time the latter contact engages contact 59. In this case the magnet 65 and contact 58 are connected directly in series at each station.

In these cases (Figs. 20 and 21) also, 35 magnets 65 may operate recording mechanism as in my said co-pending application.

In Fig. 22 is shown the connections for 40 a duplex terminal. In this case, transmitting contacts 58 and 59, and magnet 65 of the transmitting machine, are connected in a local circuit with the coils of a main line transmitter 148, the magnet 65 of this machine acting to produce a home record, as stated in connection with Figs. 19, 20 and 45 21. The signals from a distance are received on main line relay 149, which controls a local relay circuit 150, in which is connected a magnet 65' adapted to operate receiving mechanism only. In this case one 50 machine transmits the signals to a distant point, while the other machine receives them. In this diagram, 151 indicates the source of signal current at the terminal shown, and 152 the artificial line, while 153 represents the main line supposed to pass to a terminal which is a duplicate of that shown.

It will be noted that in this machine the 55 starting of the contact into operation to transmit the code impulses is absolutely dependent on the operation of magnet 65. In other words, transmission cannot be effected if magnet 65 is inoperative. This feature of the machine makes it especially adapted

to Morse methods of operation, as it makes 65 it possible to stop any sending operator by merely opening the line at another station, which corresponds to the so-called Morse "break." This will be apparent from any 70 of the diagrams, Figs. 19 to 21. Any operator may transmit as long as the line remains closed at the other stations, but if the operator at one of the other stations should open the line, the machine sending 75 at another station would be rendered inoperative during such time on account of the fact that the circuit of his magnet 65 in Figs. 19 and 21, and of relay 143 in Fig. 20, is open and out of his control.

The specific mechanism here shown and 80 described may be modified without departing from the invention as claimed.

What I claim is:

1. Apparatus for electrical signaling, comprising a balance and a power driven 85 escapement for imparting motion thereto, a timing shaft controlled by said balance, a series of members movable with said shaft, a series of selecting elements adapted to be operated in succession by said members, a 90 transmitting switch mechanically operated by said elements, keyboard operated mechanical permutation mechanism to select certain of said elements and in combination with said members selectively control 95 said elements.

2. Apparatus for electrical signaling, comprising a movable switch contact, a series of mechanical elements common to 100 said contact and arranged to individually operate the same, mechanical means to time the operation of said elements, and electrical means controlled by said switch to control the starting of said timing means.

3. Apparatus for electrical signaling, 105 comprising a movable switch contact, a series of mechanical elements common to said contact and arranged to individually move the same, and mechanical means comprising a body having a natural period of 110 motion, to automatically time the operation of said elements.

4. Apparatus for electrical signaling, comprising a movable switch contact, a series of mechanical elements common to 115 said contact and arranged to individually operate the same, and mechanical means comprising a spring controlled balance and power operated escapement operating the same to automatically time the operation of 120 said elements.

5. Apparatus for electrical signaling, comprising a transmitting contact, a series of mechanical elements common to said 125 contact and adapted to operate the same individually, mechanical means to operate said elements in combinations corresponding to the signal to be transmitted, mechani-

- cal means to time the operation of said elements, comprising a body having a natural period of motion, mechanical means to impart motion to said body, electrically operated mechanical means controlled by said contact to start said body into motion at the commencement of a signal interval and automatic means mechanically controlled to stop said body at the end of a signal period.
6. Apparatus for electrical signaling, comprising a switch contact, mechanical means to operate said contact invariably at the commencement of each signal period, and mechanical automatic means operating said contact in varying combinations according to the signal transmitted.
7. Apparatus for electrical signaling, comprising a switch contact, a plurality of keys common to said switch contact for controlling its operation, mechanism operated by each of said keys and acting to mechanically operate said contact invariably at the commencement of each signal period, mechanical selecting mechanism operated by said keys, and power actuated mechanical means operating through said selecting mechanism to operate said contact variably according to the signal transmitted.
8. Apparatus for electrical signaling, comprising a switch contact, a plurality of keys common to said switch contact for controlling its operation, mechanism operated by each of said keys and acting to mechanically operate said contact invariably at the commencement of each signal period, mechanical selecting mechanism operated by said keys, power actuated mechanical means operating through said selecting mechanism to operate said contact variably according to the signal transmitted, and means to automatically retard the operation of said switch by said invariably acting mechanism.
9. Apparatus for electrical signaling, comprising a series of mechanical elements corresponding to electrical impulses to be transmitted, said elements having two degrees of motion, but unequally normally restrained from motion in two degrees, means tending to operate said elements in succession, and selective means to positively lock said elements from motion in the way of least restraint and compel motion in the direction of greatest restraint, and mechanism operating to transmit electrical impulses corresponding to the elements so operated.
10. Apparatus for electrical signaling, comprising a series of mechanical elements corresponding to electrical impulses to be transmitted, said elements having two degrees of motion, but unequally normally restrained from motion in two degrees, means tending to operate said elements in succession, and selective means to positively lock
- said elements from motion in the way of least restraint, and a switch contact common to all of said elements and operative thereby in combinations according to the signal transmitted.
11. Telegraphic apparatus including a member having two degrees of motion, means to move said member in either degree, yielding means opposing the motion of said member in both degrees, and selectively operated means to oppose the motion of said member in one degree to cause it to move in the other degree against said yielding means.
12. Telegraphic apparatus including a member having two degrees of motion, means to move said member in either degree and operating for each signal independently of the character of the signal, yielding means opposing the motion of said member in both degrees, selectively operated means to oppose the motion of said member in one degree to cause it to move in the other degree against said yielding means, and a signal transmitting contact operated by said member when moving against said yielding means.
13. Apparatus for electrical signaling, comprising a series of selecting elements capable of two degrees of motion, step-by-step operating power means acting to move said elements in succession, a plurality of movable members, means to move said last mentioned members in combinations corresponding to the respective signals into the path of movement of said selecting members in one degree to cause their movement in another degree by said power means, and a transmitting switch mechanically operated by said selecting members when so moved, substantially as described.
14. Apparatus for electrical signaling, comprising a transmitting switch, a keyboard, a plurality of mechanical elements common to said switch, means mechanically operated by the keys of said keyboard to set said elements in combinations according to the signal to be transmitted, mechanism operating said switch invariably on the operation of each of said keys, power operated means to mechanically impart to said contact a different combination of movements for each signal, and means controlled by said invariably acting mechanism to start said power operated mechanism into motion.
15. Apparatus for electrical signaling, comprising a transmitting switch, a keyboard, a plurality of movable mechanical elements common to a contact of said switch, means mechanically operated by the keys of said keyboard to select certain of said elements in combinations according to the signal to be transmitted, mechanism operating said contact invariably on the operation of

each of said keys and itself mechanically operated by said keys, power operated means adapted to mechanically operate said elements and therethrough to mechanically operate said contact, and electrical means controlled by said contact and said invariably acting mechanism, to start said power means into motion.

16. Apparatus for electrical signaling, comprising a transmitting switch, a series of mechanical elements common to a moving contact of said switch, means forming an operative connection between said elements and said contact whereby said contact may be operated by any of said elements, power operated mechanical means operating said elements in successive order for each signal transmitted, and selecting means mechanically operated and co-operating with said element operating means to operate said contact variably according to the signal transmitted, and time keeping mechanism mechanically connected to said power operated means to control the same.
17. Apparatus for electrical signaling, comprising a movable transmitting contact, a series of movable transmitting elements, mechanical means forming an operative connection between said elements and said contact whereby any of said elements may operate said contact, a series of selecting elements adapted to operate upon said transmitting elements in combinations according to the signal selected, a power driven shaft, a series of cams on said shaft adapted to operate upon said transmitting elements in succession as said shaft rotates, the said operative connection between the said contact and said transmitting elements being responsive to those transmitting elements operated upon by the selecting elements, and non-responsive to the transmitting elements operated by said cams but not operated upon by said selecting elements, a spring controlled balance and escapement controlling step-by-step the movement of said shaft, a stop normally holding said balance against movement, a magnet operative to withdraw said stop from said balance to allow the same and said shaft to operate, an electric circuit including said contact and the winding of said magnet, and automatic means operating said stop at the end of a signal interval to arrest the motion of said balance.

18. Selective signaling apparatus, comprising a balance and escapement, a plurality of movable elements, means timed by said balance and escapement and operating to move said elements successively in phase with the oscillation of said balance, selectively operated means co-operative with said timed means to modify the movement of said elements in combinations correspond-

ing to the signals to be transmitted, and a transmitting switch mechanically operated by said modified movement of said elements.

19. Selective signaling apparatus, comprising a rotary shaft, power means for rotating said shaft, a balance and escapement, operatively connected to said shaft to cause it to rotate step-by-step, a plurality of movable elements, operated by said shaft in its step-by-step movement and operating to move said elements successively in phase with the oscillations of said balance, selectively operated means co-operative with said element operating means to modify the movement of said elements in combinations corresponding to the signals to be transmitted, and a transmitting switch mechanically operated by said modified movement of said elements.

20. Electrical signaling apparatus, comprising signal timing mechanism adapted to allot to the signals equal time intervals, and automatic means to retard the operation of said timing mechanism for a definite interval between succeeding signal periods when signals are being transmitted continuously.

21. Apparatus for electrical signaling, comprising mechanical signal starting means, electrical signaling means operated thereby, and automatic mechanical means to retard the said signal starting mechanism when signals are transmitted continuously.

22. Apparatus for electrical signaling, comprising electrical means to transmit the signals, power operated mechanical means to operate said electrical means, and automatic mechanism to retard the starting of said mechanical means between successive signals.

23. Selective signaling apparatus, comprising mechanism to selectively transmit electrical impulses to form successive signals, and an automatically acting mechanism to create a lag between succeeding signals when said signaling apparatus is operated continuously to transmit a series of signals.

24. Apparatus for electrical signaling comprising a transmitting switch contact member, a magnet, timing mechanism acting automatically to allot equal time intervals to each signal, mechanical operative connection between said timing mechanism, said switch contact member and said magnet to impart movement to said contact member variably at the commencement of each signal and in varying combinations thereafter according to the signal to be transmitted, and an electric circuit including said switch and magnet.

25. Apparatus for electrical signaling, comprising a transmitting switch, a balance and escapement, means operated by said balance and escapement for timing the

operation of said switch, a magnet operatively associated with said balance to control the starting thereof, and an electric circuit including said switch and the winding of 5 said magnet.

26. Apparatus for electrical signaling, comprising a series of elements, a transmitting contact, means to operate said elements selectively to cause said contact to transmit 10 to line varying electrical signals, and means controlled by signals on the same line to start into operation the element operating means.

27. Apparatus for electrical signaling, 15 comprising a series of elements, a transmitting contact, means to operate said elements in combinations to cause said contact to transmit to line varying electrical signals, means to time said signals, and means controlled by signals on said line to start into 20 operation said timing means.

28. Apparatus for electrical signaling, comprising an electrical contact, mechanism to move the same variably to transmit combinations of electrical impulses to form the 25 signals, a series of elements, means to set said elements in varying combinations to determine the combination of impulses to be transmitted, and a magnet operated by said 30 impulses and acting to control said transmitting means.

29. Apparatus for electrical signaling, comprising an electrical contact, mechanism to move the same variably to transmit combinations of electrical impulses to form the 35 signals, means to time said signals, a series of elements, means to set said elements in varying combinations to determine the combination of impulses to be transmitted, a 40 magnet operated by said signals, and means including said contact and controlled thereby to operate said magnet to start into action said timing means.

30. Apparatus for electrical signaling, 45 comprising a main line, an electrical contact, and mechanism to move the same variably to transmit over said line combinations of electrical impulses to form the signals, a magnet operated by all the combinations of 50 impulses capable of being transmitted over said line, and means operated by said magnet to control said transmitting means.

31. Apparatus for electrical signaling, 55 comprising a main line, an electrical contact, and mechanism to move the same variably to transmit over said line combinations of electrical impulses to form the signals, a magnet operated by all the combinations of 60 impulses capable of being transmitted over said line, and means operated by said magnet to start into action said contact-operating mechanism.

32. Apparatus for electrical signaling, comprising a main line, means including an electrical contact, mechanism to move said

contact variably to transmit over said line combinations of electrical impulses to form the respective signals, a series of elements, means to set said elements in varying combinations to determine the combinations of 70 impulses to be transmitted, means to time the speed of operation of said contact, and means controlled by said contact to control the starting of said timing means.

33. Selective signaling apparatus, comprising means movable variably to transmit electrical signals, means to operate said transmitting means including a shaft started into motion at the beginning of each signal, means operating invariably to time the motion of said shaft, and means carried by said shaft to keep in motion said timing means.

34. Selective signaling apparatus, comprising means to transmit electrical impulses including a transmitting contact, a rotatable shaft, selective means coöperating with said shaft to operate said contact variably to form the respective signals, means tending to rotate said shaft, means to automatically stop said shaft at the end of each signal, means acting to control said shaft invariably for each signal, and means carried by said shaft to operate said rotation controlling means.

35. Apparatus for electrical signaling, comprising variably moving means to transmit electrical signals, power means to operate said variably moving transmitting means, and invariably moving means to time the signals and kept in operation by the same power which operates the transmitting means and means to automatically stop said invariably moving means at the 100 end of each signal.

36. Transmitting apparatus for electric telegraphs, comprising a transmitting contact, a balance and escapement, and mechanism controlled by said balance and escapement to cause said contact to transmit 110 electrical signaling impulses in phase with the oscillations of said balance.

37. Transmitting apparatus for electric telegraphs, comprising a transmitting contact, a balance and escapement, and operative connection entirely mechanical between said balance and escapement and said contact to cause said contact to transmit electrical signaling impulses in phase with the oscillations of said balance.

38. Transmitting apparatus for electric telegraphs, comprising a transmitting contact, means to operate said contact to transmit a starting electrical impulse at the commencement of each signal, a balance and escapement, mechanism controlled by said contact to start said balance into motion for each signal in phase with said start impulse, and mechanism controlled by said balance and escapement to cause said contact 130

to subsequently transmit signal impulses in phase with the oscillations of said balance.

39. Transmitting apparatus for electric telegraphs, comprising a body having a natural period of vibratory motion, a single transmitting contact, operative connection entirely mechanical between said body and contact for timing the operation of said contact with respect to the movements of 5 said body, a keyboard, and operative connection entirely mechanical between said keyboard and contact for variably moving said contact.

40. Transmitting apparatus for electric telegraphs, comprising a body having a natural period of motion, a single transmitting contact, operative connection entirely mechanical between said body and contact for timing the operation of said contact with 10 respect to the movement of said body, signal selecting mechanism, and operative connection entirely mechanical between said signal selecting mechanism and contact for variably moving said contact.

41. Transmitting apparatus for electric telegraphs, comprising a balance and escapement, a single transmitting contact, operative connection entirely mechanical between said balance and contact for timing the operation of said contact with respect to the movements of said balance, a keyboard, and operative connection entirely mechanical between said keyboard and contact for selectively operating said contact.

42. Transmitting apparatus for electric telegraphs, comprising a movable transmitting contact, selective mechanism to move said contact variably according to the signals to be transmitted, a magnet and means operated thereby to control the starting of said contact operating mechanism, and a transmission line including said magnet and contact in series.

43. Apparatus for electrical signaling, comprising a series of selecting elements, means to move said elements in succession, mechanical permutation mechanism to select certain of said elements and in combination with said element moving means selectively modify the motion of said elements.

44. Apparatus for electrical signaling, comprising a rotatable shaft, means to transmit electric impulses, means carried by said shaft to operate said transmitting means, means to time the motion of said shaft, said timing means including a body capable of periodic motion, mechanical means to maintain the motion of said body, means controlled by the stopping of said body to stop the operation of said shaft, and means to stop the motion of said body.

45. Apparatus for electrical signaling, comprising a rotatable shaft, means to transmit electric impulses, means carried by said

shaft to operate said transmitting means, means to time the motion of said shaft, said timing means including a body capable of periodic motion, mechanical means to maintain the motion of said body, means controlled by the stopping of said body to stop the operation of said shaft, and means to stop the motion of said body at the end of each signal. 70

46. Apparatus for electrical signaling, comprising a rotatable shaft, means to transmit electric impulses, means carried by said shaft to operate said transmitting means, means to time the motion of said shaft, said timing means including a body capable of periodic motion, mechanical means to maintain the motion of said body, means controlled by the stopping of said body to stop the operation of said shaft, automatic means to stop the motion of said body at the end 80 of each signal.

47. Apparatus for electrical signaling, comprising a rotatable shaft, means to transmit electric impulses, means carried by said shaft to operate said transmitting means, 90 means to time the motion of said shaft, said timing means including a body capable of periodic motion, mechanical means to maintain the motion of said body, means controlled by the stopping of said body to stop 95 the operation of said shaft, automatic means to stop the motion of said body, and means to start said body in motion at the beginning of each signal.

48. Apparatus for electrical signaling, 100 comprising means to transmit varying electric code signals, a body capable of periodic motion, and means entirely mechanical intermediate between said transmitting means and said body acting to time said transmitting means and to maintain the periodic motion of said body. 105

49. Apparatus for electrical signaling, comprising means to transmit varying electric code signals, a body capable of periodic motion, a connection entirely mechanical intermediate between said transmitting means and said body acting to time said transmitting means and to maintain the periodic motion of said body, and means to allot 115 equal time intervals to all the elementary impulses forming a signal.

50. Apparatus for electrical signaling, comprising means to transmit varying electric signals, each having the same number of equal elementary unit time intervals, a body capable of periodic motion, connection entirely mechanical between said body and said transmitting means to time said signals, means to operate said transmitting means step-by-step, and means to maintain the same time relation between each elementary time interval of said signal and the intervals between succeeding operations of 120 said step-by-step action. 125

51. Apparatus for electrical signaling, comprising means to transmit varying electric code signals, a body capable of periodic motion, means entirely mechanical intermediate between said transmitting means and said body acting to time said transmitting means and to maintain the periodic motion of said body, and means to stop the motion of said body at intervals and thereby stop the operation of the transmitting means. 60
52. Apparatus for electrical signaling, comprising means to transmit varying electrical code signals, a body capable of periodic motion, means entirely mechanical intermediate between said transmitting means and said body acting to time said transmitting means and to maintain the periodic motion of said body, means to stop the motion of said body at the end of each signal and thereby stop the operation of the transmitting means, and means to start said body in motion at the beginning of each signal. 65
53. Apparatus for electrical signaling, comprising timing means, step-by-step operated transmitting means, the timing of said step-by-step operated means being controlled by said timing means, an electrical circuit over which impulses are transmitted by said transmitting means, and a magnet in said circuit acting to start said transmitting means in operation. 70
54. Apparatus for electrical signaling, comprising timing means, step-by-step operated transmitting means, the timing of said step-by-step operated means being controlled by said timing means, an electrical circuit over which impulses are transmitted by said transmitting means, and a magnet in said circuit acting to control said step-by-step operated means. 75
55. Apparatus for electrical signaling, comprising step-by-step operated transmitting means, an electrical circuit over which varying impulses are transmitted by said step-by-step operated transmitting means, a magnet in said circuit, and means controlled by said magnet to start into operation said step-by-step operated mechanism. 80
56. Apparatus for electrical signaling, comprising step-by-step operating mechanism, a magnet, said magnet acting to control said step-by-step operating mechanism, and said step-by-step operating mechanism in turn controlling the operation of said magnet. 85
57. Apparatus for electrical signaling, comprising step-by-step operating mecha-
- nism, a magnet, said magnet acting to control said step-by-step operating mechanism, and said step-by-step operating mechanism in turn controlling the transmission to said magnet of impulses varying according to the signals selected. 90
58. Apparatus for electric signaling, comprising a series of selecting elements determining the signal to be transmitted, a magnet, means to operate said magnet each time said selecting elements are operated, step-by-step operated transmitting means, said magnet acting to start said step-by-step operated mechanism into action, said step-by-step operated mechanism acting to transmit to said magnet impulses thereafter varying according to the signal selected. 95
59. Signal transmitting means, means to start said signal transmitting means into operation at the beginning of each signal period, means to time the operation of said transmitting means, automatically acting means to stop said timing means for each signal, and automatically acting means to create a lag between the stopping of said timing means and the starting of said timing means for the next succeeding signal. 100
60. Apparatus for electrical signaling, comprising a series of elements, permutation means to operate said elements in combinations according to the signal selected, a second series of elements, means to individually operate said second series in succession for each signal, and means to modify the operation of said second series according to the permutation of the elements in the first series. 105
61. Apparatus for electrical signaling, comprising a series of elements, permutation means to operate said elements in combinations according to the signal selected, a second series of elements, means to individually operate said second series in succession for each signal, means to modify the operation of said second series according to the permutation of the elements in the first series, a main line and means controlled by said second series of elements to transmit to said line a varying series of impulses according to the operation of the said second series of elements. 110
